UNITED STATES PATENT OFFICE.

CHARLES W. SMITH, OF NORWALK, OHIO.

EXTENSIBLE GRILLE.

SPECIFICATION forming part of Letters Patent No. 747,095, dated December 15, 1903.

Application filed August 5, 1903. Serial No. 168,351. (No model.)

To all whom it may concern:

Be it known that I, CHARLES W. SMITH, a citizen of the United States, residing at Norwalk, in the county of Huron and State of Ohio, have invented certain new and useful Improvements in Extensible Grilles; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in extensible grilles which may be fitted to openings of various widths without the necessity of cutting parts and without destroying the symmetry of the design of the grillework.

More specifically my invention comprises an extensible grille having end sections of scrollwork and a central scroll-section so constructed that the ends thereof will interlock with the end sections without in any way affecting the general appearance of the design of the grillework.

The invention consists, further, in various details of construction and arrangements of parts, which will be hereinafter fully described and then specifically defined in the appended claims.

I illustrate my invention in the accompanying drawings, in which—

Figure 1 is a side elevation of the grille-work, showing the sections extended. Fig. 2 is a similar view showing the parts pushed together. Fig. 3 is a side elevation of the parts disconnected, and Fig. 4 is a detail sectional view showing the manner of fastening the grille-sections together.

Reference now being had to the details of the drawings by letter, A A designate the end sections of the grille-work, which may be of any design and adapted to be fastened to the opposite sides of the opening in which the grille-work is to be located. These end sections are fastened in any suitable way to the casing of the opening, and in the design shown in the drawings a bracket-arm B extends in substantially a horizontal position from the end sections and is provided with a series

of beads C, disposed at intervals in the upper edge of said bracket-arm, while the scroll E extends laterally from the end section and above the bracket-arm B, and the top edge of said scroll E is preferably in a plane parallel to the plane in which the horizontally-disposed bracket-arm B is disposed, thereby affording two horizontal parallel portions 60 against which parts of the intermediate scroll-section F contact, as shown clearly in the drawings. Said intermediate section F is adapted to be held by a strip in one of its upper longitudinal edges to a casing of the opening and is provided with a strip F', forming its lower marginal edge, the ends f' of which strip project beyond the strip F'', which forms its upper marginal edge, said ends adapted to rest upon the beads C, both when the sections are pushed together, as shown in Fig. 2, or as disclosed in Fig. 1, when extended. A scroll K is formed upon each end of the intermediate section F and has, preferably, a projection K' on the outer edge of each scroll, 75 which is adapted to contact with the upper edge E of the scroll upon the end pieces. Upon reference to Fig. 1 of the drawings it will be observed that a space intervenes between the upper marginal edges of the end 80 scroll-sections and the intermediate sections, thus allowing the sections to be closed together, if desired, or assume the position shown in Fig. 2, adapting the sections to fit openings of different widths and at the same 85 time without in any way disfiguring the design of the grille-work. As the sections are closed together the ends of the section F will assume the positions shown in Fig. 2 and the lugs or projections K' will be positioned as 90 shown in Fig. 2.

From the foregoing it will be observed that by the provision of my improved extensible grille-work I may be able to fit openings of any width by having the central sections of 95 different lengths adapted to fit openings of various widths, the adjustment of from ten to fifteen inches being allowed for stock-patterns.

In order to hold the grille-sections together, 100 I provide, preferably, screws C', which pass through the marginal strips of the sections and through the beading C, as shown clearly in Fig. 4 of the drawings.

While I have shown a particular design of grillework, it will be understood that any shape or figuration of grillework may be employed without in any way departing from the spirit of the invention, the essential features being the provision of a grillework which may be extensible, adapted for stock-patterns for openings of various widths, at the same time without in any way destroying the symmetry of the design.

Having thus fully described my invention, what I claim as new, and desire to secure by Letters Patent, is—

1. An extensible grillework comprising end sections provided with scrolls, a bracket extension, an intermediate section having portions thereof in contact with said bracket extension, a scroll with extensions held adjacent to the scrolls of the end sections, the various sections adapted to interlock and to be adjustably held in different positions, as set forth.

2. An extensible grille comprising end sections having bracket extensions, beads on the

latter, and an intermediate scroll-section having a strip, the ends of which are adapted to be adjustably held adjacent to the said beads and scrolls on the sections adapted to interlock and form symmetrical designs, as set forth.

3. An extensible grille for openings comprising end sections, each having a bracket extension, a scroll projecting laterally from each end section having an edge in a plane parallel to the plane in which said bracket extension is disposed, an intermediate section having lugs or projections designed to be positioned adjacent to the edge of the laterally-projecting scrolls on the sections, thereby forming a symmetrical design for the grille-work whether the same is extended or closed together and interlocked, as set forth.

In testimony whereof I hereunto affix my signature in presence of two witnesses.

CHARLES W. SMITH.
